STABILIZED FATTY COMPOSITIONS AND
STABILIZERS THEREFOR

Noel H. Kuhrt, Rochester, N. Y., assignor to Eastman Kodak Company, Rochester, N. Y., a corporation of New Jersey

No Drawing. Application January 15, 1952,
Serial No. 266,594

10 Claims. (Cl. 99—163)

1 This invention relates to fatty compositions characterized by improved stability against oxidation and to stabilizer compositions useful as additives to fatty materials.

The susceptibility of fatty materials to oxidation and resultant rancidity makes it necessary to stabilize fatty materials normally subject to oxidation, and particularly edible fats and oils, before commercial use. The fatty materials subject to the deleterious effects of oxidation are usually characterized by the presence of unsaturated components, and such fatty materials include solid fats, fatty oils and fat-forming fatty acids. The fatty materials used most widely in edible products are those materials consisting predominantly of fatty triglycerides as typified by the animal fats and vegetable oils, whether unhydrogenated or partially hydrogenated, and such materials must, of course, be stabilized against peroxide formation and resultant oxidative rancidity.

It is accordingly an object of this invention to provide new fatty compositions characterized by improved stability against oxidative rancidity.

It is another object of the invention to provide new stabilizer compositions especially effective for incorporation in fatty materials normally subject to oxidation.

It is a further object of the invention to provide new stabilized compositions consisting predominantly of fatty triglycerides.

Another object of the invention is to stabilize edible fatty materials, such as are commonly used for human consumption, against objectionable development of oxidative rancidity under normal storage conditions.

Another object of the invention is to provide improved animal fat and vegetable oil compositions, and particularly shortening compositions.

Another object of the invention is to provide fatty compositions effectively stabilized against excessive oxidation but retaining their desirable physical and chemical characteristics.

Other objects will be apparent from the description and claims which follow.

These and other objects are attained in accordance with this invention which comprises stabilizing fatty material normally subject to oxidation by incorporating therein a solution of glycine and phosphoric acid in a polyalkylene oxide derivative of a fatty acid partial ester of a polyhydric alcohol or an anhydride of such alcohol.

The invention is applicable for stabilizing any of the well-known fatty materials normally sub-

ject to oxidation, including both solid fats and fatty oils, and particularly the fatty materials consisting predominantly of fatty triglycerides or fat-forming fatty acids normally subject to oxidation. The fatty triglycerides include animal fats such as lard, tallow and the like, and vegetable oils such as cottonseed oil, soybean oil, peanut oil, coconut oil, corn oil and the like, whether unhydrogenated or partially hydrogenated as in the usual vegetable oil shortenings. The fatty acids include any of the pure or mixed unsaturated fatty acids as typified by oleic and linoleic acids.

2 The fatty materials are stabilized in accordance with this invention by incorporating therein a minor amount of a solution of glycine and phosphoric acid in a polyalkylene oxide derivative of a fatty acid partial ester of a polyhydric alcohol or its anhydride, preferably at a temperature of 50–95° C. The polyalkylene oxide derivatives which can be employed in practicing this invention are the well-known materials obtained by reacting ethylene oxide or similar alkylene oxide, such as 1,2-propylene oxide or 1,3-propylene oxide, or a polyalkylene oxide polymer with a fatty acid partial ester of a polyhydric alcohol or anhydride. The polyoxyalkylene derivatives employed are preferably those having a melting point not higher than 100° C., and desirably those obtained by reacting from about 5 to 60 moles, or more desirably about 16 to 25 moles, of ethylene oxide with a fatty acid monoester of a hexitol such as sorbitol or mannitol or the corresponding hexitan (or hexitol anhydride) such as sorbitan or mannan, the fatty acid portion preferably being of a fat-forming higher fatty acid having at least twelve carbon atoms in the fatty acid molecule such as lauric acid, stearic acid, oleic acid, palmitic acid or the like. Particularly suitable materials are the polyoxyethylene derivatives of sorbitan monooleate, sorbitan monostearate, sorbitan monopalmitate or similar sorbitan fatty acid monoester, such derivatives being obtained by reacting the sorbitan monoester with 20 to 25 moles of ethylene oxide in accordance with well-known methods.

The glycine and phosphoric acid are dissolved in the polyoxyethylene derivative either with such derivative in liquid form or by use of a suitable mutual solvent such as glycerine. Glycine and phosphoric acid are desirably employed in the form of the free acids but materials furnishing glycine and phosphoric acid in the final composition can be used and are within the scope of this invention. Thus, for example, a crude

soy protein hydrolysate can be employed to furnish the desired glycine, and a suitable salt of phosphoric acid can be employed, such as sodium phosphate, to furnish the phosphoric acid within the scope of this invention. The glycine and phosphoric acid are desirably employed with the phosphoric acid present in an amount not greater than twice the weight of glycine, and are preferably employed in approximately equal amounts by weight although larger proportions of glycine are not particularly objectionable and can be employed if desired.

The solution of glycine and phosphoric acid in the polyoxyethylene sorbitan monoester or similar derivative is readily incorporated in the fatty material to be stabilized, preferably at a temperature at which both the fatty material and the stabilizer composition are liquid, and desirably at a temperature of 50-95° C. Higher temperatures are usually not necessary and are undesirable from the standpoint of obtaining optimum stability. Effective stabilization is obtained with amounts of the glycine and phosphoric acid each of from 0.00005% to 0.02% by weight based on the total composition weight although higher amounts such as 0.1% or even 0.5% or higher of each of the glycine and phosphoric acid can be used if desired. The amount of polyoxyethylene derivative in the fatty composition is desirably kept below about 5% of the total composition weight but the amount of such derivative can be varied by varying the concentration of glycine and phosphoric acid in solution in the derivative. In the preferred compositions embodying the invention, the compositions comprise at least 85% by weight of fatty triglycerides.

The compositions prepared in accordance with this invention were evaluated for stability by the Active Oxygen Method (AOM) wherein the peroxide content in millimols per kilogram of fat was checked at periodic intervals while a sample of the composition was heated at 96° C. with air bubbling through the sample. A peroxide value of 20 was considered to be the maximum permissible value for commercial compositions, and the stabilized compositions embodying this invention were tested to determine their stability in terms of the time necessary to reach a peroxide value of 20 under the accelerated test conditions as compared to the time required for an unstabilized control sample.

The invention is illustrated by the following examples of certain preferred embodiments which are included only for purposes of illustration and which are not intended to limit the scope of the invention unless otherwise specifically indicated.

Example 1

A solution of 0.02% by weight of glycine and 0.02% by weight of phosphoric acid in polyoxyethylene sorbitan monolaurate, obtained by reacting 20 moles of ethylene oxide with 1 mole of sorbitan monolaurate, was mixed with partially hydrogenated cottonseed oil shortening at a temperature of 60° C., the stabilizer solution amounting to 1.5% by the weight of such shortening. The AOM stability of the resulting stabilized composition, based on the time necessary to reach a peroxide value of 20, was found to have increased about 40% over that of the control sample.

Example 2

Lard was stabilized in accordance with this

invention to give a composition containing 0.0003% by weight of glycine, 0.0003% by weight of phosphoric acid, and 1.5% by weight of polyoxyethylene sorbitan monooleate in which the polyoxyethylene amounted to 20 molar proportions. The resulting stabilized lard by the AOM test reached a peroxide value of 20 after 20 hours as compared to 7 hours for a control sample of the same lard base.

Example 3

A partially hydrogenated cottonseed oil composition was stabilized by the addition thereto of 1.5% by weight based on the weight of such composition of a solution of 0.02% glycine and 0.02% phosphoric acid in polyoxyethylene sorbitan monooleate. The stability of the composition (AOM) was increased 40% by the addition of the stabilizer composition.

Example 4

Lard stabilized with 1.5% by weight of a solution of 0.02% glycine and 0.02% phosphoric acid in polyoxyethylene²⁰ sorbitan monolaurate showed an increase in stability of about 115% by the AOM test.

Similarly improved results are obtained with other stabilized compositions embodying this invention; and although the invention has been described in considerable detail with reference to certain preferred embodiments, it will be understood that variations and modifications can be effected within the spirit and scope of the invention as described hereinabove and as defined in the appended claims.

I claim:

1. A fatty composition consisting predominantly of fatty material normally subject to oxidation and having admixed therewith a solution of glycine and phosphoric acid in a polyalkylene oxide derivative of a fatty acid partial ester of a compound selected from the class consisting of polyhydric alcohols and their anhydrides.
2. A normally solid fat having incorporated therein a solution of glycine and phosphoric acid in a polyoxyethylene derivative of a fatty acid partial ester of a hexitan.
3. A fatty oil having incorporated therein a solution of glycine and phosphoric acid in a polyoxyethylene derivative of a fatty acid partial ester of a hexitan.
4. A fatty composition consisting predominantly of fatty acid triglycerides and having dispersed therein a minor amount of a solution of glycine and phosphoric acid in a polyoxyethylene derivative of a fatty acid monoester of sorbitan.
5. A fatty triglyceride composition having incorporated therein a solution of glycine and phosphoric acid in a polyoxyethylene derivative of a fatty acid monoester of sorbitan, said glycine and said phosphoric acid each being present in an amount of not more than about 0.02% by weight based on the total weight of said composition, said phosphoric acid being present in an amount not greater than twice the weight of said glycine.
6. A fatty composition comprising at least 85% by weight of fatty triglycerides, from 0.00005% to 0.02% by weight of glycine, and from 0.00005% to 0.02% by weight of phosphoric acid, all based on the total composition weight, said glycine and phosphoric acid being present in solution in a polyoxyethylene derivative of a fatty acid monoester of sorbitan.
7. A shortening having incorporated therein a solution of glycine and phosphoric acid in a poly-

5

oxyethylene derivative of a higher fatty acid monoester of sorbitan.

8. A stabilizer composition for stabilizing fatty material comprising a solution of glycine and phosphoric acid in a polyalkylene oxide derivative of a fatty acid partial ester of a compound selected from the class consisting of polyhydric alcohols and their anhydrides.

9. A stabilizer for fatty material comprising a solution of glycine and phosphoric acid in a polyoxyethylene derivative of a fatty acid mono-
ester of sorbitan.

10. A stabilizer for fatty material comprising a solution of glycine and phosphoric acid in a

6

polyoxyethylene derivative of a fatty acid mono-
ester of sorbitan, said phosphoric acid being pres-
ent in an amount not greater than twice the
weight of said glycine.
